CARVING PLATTER

Arthur L. Margolis, Glencoe, Ill., assignor to The Dearborn Company, Chicago, Ill., a corporation of Illinois

Filed Mar. 24, 1958, Ser. No. 723,211

9 Claims. (Cl. 146—215)

This invention relates to an improved carving platter or the like, and more specifically relates to an improved carving platter of the type having spike-like impaling means extending from the carving surface thereof.

Carving platters of the type having spike-like impaling means extending from the carving surface thereof are well known. When storing the device, it is impossible to stack other boxes, or dishes, or pieces, on the platter as the spikes either fail to provide a firm support or may scratch or otherwise damage the part resting thereon.

Another deficiency in existing platters has been observed in that, when one handles the carving platter, frequently the handler may scratch himself on the sharpened impaling spikes, and this is a source of great annoyance which is associated with existing carving platters.

Thus, one object of this invention is to provide a spiked carving platter wherein the spiked impaling means thereof may be selectively advanced to an operative impaling position or may be selectively retracted to a non-protruding position below the carving surface of the platter, so as to avoid the deficiencies above noted.

Another object of this invention is to provide a new and improved carving platter which not only avoids the aforesaid deficiencies heretofore found in carving platters but at the same time provides a carving platter that is characterized by its simplicity of construction and its efficiency of operation.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawings, in which:

Figure 1 is a perspective view of a carving platter embodying my invention.

Figure 2 is a fragmentary side elevation view, with portions in vertical cross-section through the impaling spike means of the platter.

Figure 3 is an enlarged top plan view of one of the spiked, impaling means shown in Figures 1 and 2.

Figure 4 is a cross-section view, with parts broken away, taken substantially on line 4—4 of Figure 3.

Figure 5 is a top plan view of a two-spike type impaling means.

Figure 6 is a top plan view of a modified form of impaling means showing a single-spiked impaler.

Figure 7 is a cross-section view taken on line 7—7 of Figure 6.

Figure 8 is a fragmentary vertical cross-section view of a portion of an impaling means, showing a further modification of construction.

Referring now to the drawings, there is shown in Figure 1 a carving platter generally indicated at 10, which comprises a carving board 12 of generally rectangular configuration provided with four support legs 14 depending from the carving board 12 and spaced at the corners

thereof. The carving board 12 provides an upper carving surface 16, which is surrounded by a peripheral gutter means 18 for receiving drainage from the carving surface. The arrangement of the legs 14 relative to the plane of the carving surface 16 is such that when the carving platter 10 is positioned on a horizontal surface, the board is slightly inclined so that drainage from surface 16 and which may be received by gutter 18 will gravitate toward an enlarged drainage-receiving well 20 formed at one end of the platter.

Within the confines of the carving surface 16 there is formed a depressed, branched, gutter means 22 including a main gutter 24 and a plurality of branch gutters 26 which radiate from and drain into main gutter 24. The gutter 18 24 is arranged for emptying into the drainage-receiving well 20, as seen in Figure 1.

There is provided a plurality of material-impaling means carried on the carving board, said impaling means being interstitially disposed relative to the branched gutter means 24—26. The impaling means are more specifically seen in Figures 2 to 4, and each impaling unit includes a female-threaded tubular insert 30 which is press-fit into a vertical bore formed in the carving board 12 so that the upper end of the tubular insert 30 lies substantially flush with the carving surface 16. There is removably positioned in the threaded tubular insert 30 a threaded plug member 32 having impaling spikes 34 extending upwardly therefrom, and having a stem 36 with a head 38 extending downwardly therefrom. The stem 36 may be formed integral with plug member 32 and spikes 34 may be connected in any appropriate manner to plug 32, such as by being press-fit into bores therein or being stud-welded thereto.

The plug 32 may be selectively manipulated through stem 36 to an uppermost, operative, position in which the impaling spikes 34 extending upwardly from the carving surface 16, as seen in Figure 1, for the purpose of having the material to be carved impaled thereon. In their retracted position, the impaling means 34 are wholly withdrawn, to be inoperative, below the plane of the carving surface 16, as seen in detail in the cross-sectional view on the left portion of Figure 2.

The length of the stem 36 with the head 38 thereon is such that when the plug 32 is in its operative position with the impaling means 34 extending upwardly from the carving surface 16, then the head 38 of stem 36 extends below the lowermost reach of tubular insert 30, so that one may still grasp head 38 to effect manipulation of the plug 34. The under portion of board 12 is recessed at 39 adjacent the lower end of insert 30 to accommodate grasping of head 38. It is also seen that the spacing of the carving board 12 above the plane of the lower terminus of the support legs 14 is such, and the length of stem 36 with head 38 thereon is such, and the length of insert 30 is such that when the plug 32 is in its retracted position with the impaling means positioned wholly below the plane of the carving surface 16, then the plug 32 is still threaded to insert 30 and the lowermost reach of head 38 on stem 36 is still spaced above the plane of the support surface, so that there is no interference by head 38 with the support surface when the impaling means are in retracted position.

Means are provided for insuring a substantially leak-proof connection between the plug 32 and the tubular insert 30 when the impaling spikes 34 are in their operatively extended position. One such means of insuring against leakage is to provide a plurality of close-fitting threads between the plug 32 and the tubular casing 30, and by providing fine machine threads with a close fit, a substantially leak-proof connection is attained. As an alternative construction, as seen in Figure 8, there is provided a sealing gasket in the form of an O-ring 42

carried in an annular recess 44 formed in tubular casing 35 and arranged to engage a shoulder 46 formed on plug member 32, to effect a seal to prevent leakage between the plug 32 and tubular insert 30.

There are also provided stop means for limiting the upper axial movement of the plug 32 relative to tubular insert 30 when the spike means have been advanced to their uppermost, operative position. A number of alternate forms of such stop means are disclosed herein. In the preferred form, the tubular insert 30 is formed with an inturned annular flange 48 at its upper end, and the plug member 32 is formed with a cooperating shoulder 49 for complementary mating with the inturned flange 48. As best seen in Figure 4, when the plug member 32 abuts the inwardly extending flange 48, the upper surface 50 of plug member 32 is disposed in planar alignment with the terminus of insert 30, thereby providing a substantially flush surface with the carving surface 16. It will be seen that the flange 48 limits the movement of the plug 32 only in the upward direction.

An alternative stop means is shown in Figure 7 wherein in the head 38' on the stem member 36' is of greater diameter than the lower terminus of the tubular insert 30 and is adapted to engage the lower terminus of the insert 30 at a point where the impaling point 34' extends fully from the upper terminus of the tubular insert 30.

Figure 3 illustrates the triangular arrangement of impaling spikes 34 about the center of plug 32 when three spikes are provided on a plug 32; Figure 7 illustrates the axial arrangement of a single spike when a single spike 34' extends from plug 32'; and Figure 5 illustrates the diametrical disposition of spikes when a pair of impaling spikes 34" extend from plug member 32". Any of the various impaling units herein disclosed may be used in any combination, as desired, on a carving board.

It will be seen from the foregoing that there has been provided an improved carving platter wherein the material-impaling means thereof are arranged to be selectively extended to an operative, material-impaling position or retracted to a completely recessed position below the carving surface of the platter.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new, and desire to secure by Letters Patent of the United States, is:

1. A carving platter comprising, in combination, means defining a substantially imperforate carving board which provides thereon a carving surface with gutter means therein for draining the carving surface; and material-impaling means carried on said carving board, said impaling means including at least one female-threaded tubular insert extending through the board and terminating at its upper end substantially in the plane of the carving surface, and an elongated impaling-spike-carrying plug threaded in said tubular insert and being selectively positionable axially in an operative position, wherein the impaling-spikes extend upwardly from the carving surface, or in an inoperative position, wherein the impaling-spikes are fully retracted below the plane of the carving surface.

2. A carving platter comprising, in combination, means defining a substantially imperforate carving board which provides thereon a carving surface with gutter means therein for draining the carving surface; spaced support means depending from said carving board for spacing the carving board above a support surface; and material-impaling means carried on said carving board, said impaling means including at least one female-threaded tubu-

lar insert extending through the board and terminating at its upper end substantially in the plane of the carving surface, an elongated impaling-spike-carrying plug threaded in said tubular insert and being selectively positionable axially in an operative position, wherein the impaling-spikes extend upwardly from the carving surface, or in an inoperative position, wherein the impaling-spikes are fully retracted below the plane of the carving surface, said plug having a manipulable stem extending therefrom oppositely of said impaling-spikes, the length of said stem being such that when the plug is in said operative position, said stem extends below the lower end of the tubular insert to be grasped, and when the impaling-spikes are fully retracted the lower end of the stem is spaced above the plane of the terminus of the platter's support means, so that the platter may be positioned on a support surface without interference with the stem of the impaling means.

3. Impaling-spike means for a carving platter comprising, in combination, an axially elongated female-threaded annular casing, a male plug threaded in said female casing, a manually operable, headed stem carried by said plug and extending outwardly of said female casing for all positions of the plug in said casing, at least one impaling-spike carried by said plug and extending therefrom in a direction opposite from said headed stem, means providing a substantially leak-proof connection between the plug and casing when the impaling-spike is in its operative, extended, condition, and stop means including a portion of said casing for limiting advancing axial movement of the plug relative to the annular casing when the impaling-spike means carried by the plug has been advanced to its operative position.

4. Impaling-spike means for a carving platter comprising, in combination, an axially elongated female-threaded annular casing, a male plug threaded in said female casing, a manually operable stem carried by said plug and extending outwardly of said female casing for all positions of the plug in said casing, at least one impaling-spike carried by said plug and extending therefrom in a direction opposite from said stem, the axial length of said annular casing being such that the impaling-spikes carried by the plug may be withdrawn to a position located intermediate the ends of the annular casing while the plug is still threaded to the annular casing.

5. An impaling-spike means as set forth in claim 3, wherein the threaded connection between said annular casing and plug include fine machine threads to provide said substantially leak-free connection therebetween.

6. An impaling-spike means as set forth in claim 3 including O-ring type sealing means between the casing and plug for assisting in effecting said substantially leak-free connection therebetween.

7. An impaling-spike means as set forth in claim 3, wherein said stop means including means on said plug arranged to engage one end of said casing.

8. An impaling-spike means as set forth in claim 3, wherein said stop means including an inturned lip at one end of the casing and means on the plug for engaging said inturned lip.

9. An impaling-spike means as set forth in claim 3, wherein said stop means includes an enlarged head on said stem adapted to abut one end of the annular casing.
